LESLIE R. N. CARVALHO, OF BROOKLYN, NEW YORK, ASSIGNOR TO CLOSURE SERVICE CORPORATION, OF BROOKLYN, NEW YORK, A CORPORATION OF NEW YORK.

RECEPTACLE CLOSURE.

1,413,654.

Specification of Letters Patent. Patented Apr. 25, 1922.

Application filed February 4, 1921. Serial No. 442,393.

To all whom it may concern:

Be it known that I, LESLIE R. N. CARVALHO, a citizen of the United States, residing at Brooklyn, in the county of Kings and 5 State of New York, have invented certain new and useful Improvements in Receptacle Closures, of which the following is a specification.

This invention relates to a receptacle 10 closure and method of manufacture, the same embodying certain features of, and being in the nature of an improvement over, the structures shown and described in my pending applications, Serial No. 300,462, 15 filed May 28, 1919; Serial No. 367,061, filed March 19, 1920, and Serial No. 413,649, filed Sept. 20, 1920.

An object of the present improvement is to provide a closure having all of the advantages 20 of the structures shown in said pending applications, and at the same time furnishing a more efficient means than any of the previous structures for effecting an air-tight engagement between the closure 25 and the receptacle.

A further object is to so shape the sheet metal portion of the closure that it will furnish means enabling the gasket element to fully and properly perform its sealing 30 function without likelihood of any portion of the gasket occupying a position between the upper edge of the receptacle and the adjacent under surface portion of the closure.

35 A further object is to provide an improved method for manufacturing the closure.

Other objects and aims of the invention, more or less specific than those referred to above, will be in part obvious and in part 40 pointed out in the course of the following description of the elements, combinations, arrangements of parts and applications of principles, constituting the invention; and the scope of protection contemplated will 45 be indicated in the appended claims.

In the accompanying drawings which are to be taken as a part of this specification; and in which I have shown merely a preferred form of embodiment:—

50 Figure 1 is a side elevational view of a portion of a receptacle illustrating a closure applied thereto constructed in accordance with this invention, part of the view being broken away and shown in vertical section for illustrating the condition of

the several parts as they appear when the closure is fully applied.

Figure 2 is an enlarged detailed sectional view similar to a portion of Fig. 1, but illustrating the parts of the closure as they 60 appear before application of the closure to a receptacle, and

Figure 3 is a view similar to that seen in Fig. 2, but showing the condition of the closure as it appears at one time during its 65 manufacture.

Referring to the drawings for describing in detail the structure which is illustrated therein, the reference character L indicates the receptacle, and the reference character 70 G indicates the closure. The receptacle may be of any desired character, but in the instance illustrated consists simply of an ordinary jelly tumbler. The upper annular edge surface, as 1, of the receptacle is preferably rounded somewhat, as indicated, for facilitating the application of the closure 75 thereto.

The outer circumferential surface, as 2, of the receptacle, for engagement by the 80 closure, is preferably smooth and may, if desired, be tapered downwardly and inwardly a slight degree.

The closure G consists of a single piece of sheet metal shaped to provide what may 85 be termed a body portion 3 and an annular marginal bead portion 4. The body portion 3 is adapted to close the upper end of the receptacle while the bead portion comprises means for receiving and gripping the walls 90 of the receptacle.

The bead 4 consists of an inner upwardly extending wall 5, a top wall 6, an outer downwardly extending wall 7, and an inwardly and upwardly extending wall 8 95 formed at the lower edge of wall 7 constituting, in effect, a wire edge internally of wall 7.

The wall 5 of the bead is adapted to stand within the open end of the receptacle and to 100 lie adjacent to the inner annular surface of the wall of the receptacle approximately as indicated.

The wall 6 of the bead is adapted to overlie the upper annular edge of the receptacle. 105

The wall 7 of the bead is adapted to extend downwardly over the outer surface of the wall of the receptacle.

The wall 8 serves to directly engage the receptacle and may be conveniently referred 110

to as the receptacle gripping flange. By reason of its position relative to the other walls, it is rendered resilient, the degree of resiliency being dependent somewhat upon the character and relative position and size of the flange and the wall 7.

A ring, or gasket H, of suitably resilient material, such as rubber composition, is positioned within the bead 4.

In order that the important features of this invention may be more readily understood and appreciated, the illustration Fig. 1 contains a heavy dotted line, as 9, continuing from one portion of the side wall 7 to the top wall 6 to illustrate the shape of this part of the cap as the same has been constructed heretofore, disclosed in said prior applications. Note that the line 9 is a curve continuing unbrokenly the curve of the inner surface of the lower portion of the wall 7 and that it defines a space between said wall and the wall 6 and the receptacle of gradually decreasing size upwardly and over the upper edge of the receptacle upwardly into which space the gasket is naturally forced when the closure is applied on to the receptacle.

It has been found in practice that where portions of the gasket material are thus forced upwardly to sealing position over the upper edge of the receptacle, the result is not always uniform; that is, at certain points around the circumference of the receptacle a greater bulk of the gasket is forced over the upper edge of the receptacle than at other points so that a defective seal results.

It is accordingly a prime object of the present invention to provide means adapted to prevent any part, or parts, of the gasket material from being forced to sealing position over the upper edge of the receptacle, and one means for accomplishing this result is herein illustrated to consist of enlarging the bead 4 at the junction between the walls 6 and 7 so as to form a pocket, as 10, therein, lying just outside of the upper edge of the receptacle, into which pocket a suitable part of the upper annular edge portion of the gasket may find its way when the closure is forced down on to the receptacle. The pocket 10 is of appropriate size so that it will properly accommodate the mentioned portion of the gasket and thereby obviate likelihood of any part of the gasket being forced to sealing position directly above the upper edge of the receptacle.

It is also an important feature of the invention to provide within the bead an annular inset wall portion 11 just beneath the pocket. This wall portion is formed directly at the lower end of the outer wall portion, as 12, of the pocket and is produced preferably by bending in the material of the bead so that said wall portions 11 and 12 stand substantially vertical and practically

parallel with the adjacent outer surface of the receptacle and considerably nearer to the receptacle than the adjacent portion of wall 7 beneath the wall portion 11. In bending in the material of the bead to provide the wall portion 11, an annular ledge, or shoulder, 13 is formed within the bead facing downwardly and this is of material importance as will be presently pointed out.

All of the walls are rounded from one to the other so that the exterior of the closure throughout is suitably smooth and attractive. No parts are present which could in any way injure the hands of an operator attempting to remove the closure. The only raw edge of metal present is that at the upper edge of the gripping flange 8, and this is in such a position that the operator's hands cannot possibly reach it. It is also so positioned that it is entirely outside the receptacle; that is in a position such that the contents of the receptacle may have no access to it.

The gripping flange 8 may extend continuously and uninterruptedly throughout the circumference of the closure, as indicated, or it may be corrugated, as shown in the pending application, Serial No. 413,649.

The ring, or gasket, H is indicated in Fig. 3 as it appears in its normal condition; that is, before it is compressed or distorted by the formation of the gripping flange.

In the manufacture of these closures, the gasket is placed in position within the wall 7, substantially as indicated by the full lines in Fig. 3, before said wall is turned 100 for forming the gripping flange, and in thus placing the gasket it engages the ledge 13 which prevents it from moving readily further toward the wall 6. The ledge 13 thus serves to insure that the gasket will always 105 occupy a given position relative to the walls 6 and 7 at the time when the wall 7 is bent to form the gripping flange.

In turning the wall 7 to form the gripping flange the gasket is forced upwardly 110 toward the wall 6. In this movement the gasket is made to slide over the shoulder, or ledge, 13, which, of course, produces a certain amount of distortion of the gasket so that an annular portion thereof, as 14, is 115 made to project inwardly to a position where it will be positively engaged by the receptacle when the cap is applied to the receptacle.

The position of the gasket, after the formation of the gripping flange, is indicated by the dotted lines in Fig. 3, and in this figure, as well as in Fig. 2, it will be seen that said wall portion 11 constitutes a sort of pivot, or ridge, about which the gasket is 125 bent when the closure is applied to a receptacle.

When the closure is manufactured; that is, before it is applied to a receptacle, the gripping flange inclines inwardly, as indi- 130

cated by the full lines in Fig. 2. In this position the upper edge of the flange extends inwardly of the gasket and is adapted when the closure is applied to a receptacle to be 5 forced backwardly, or outwardly, by the receptacle and to thereby generate a considerable pressure against the receptacle serving to hold the closure applied.

As the closure is being pressed on to the 10 receptacle, and the gripping flange is forced outwardly, the upper edge of the receptacle comes into contact with the portion 14 of the gasket. The outward movement of the gripping flange, under pressure from the 15 receptacle has already compressed and squeezed the gasket to some extent between the gripping flange and the wall 7, so that it has been made to practically fill the space within the bead beneath the shoulder 13. 20 The gasket has, at this time, been formed with a shoulder upon itself engaging beneath and against the shoulder 13 serving to prevent, or overcome, the tendency of the gasket to be moved bodily upwardly as the 25 receptacle passes above the upper edge of the gripping flange.

At the same time, a certain proportion of the lower part of the gasket has been squeezed upwardly to increase the bulk of 30 gasket material lying inside the wall portion 11.

As the closure is forced downwardly, and the receptacle comes into engagement with the portion 14 of the gasket, the portion 14 35 is pressed backwardly toward the wall portion 11 and very tightly compressed between said wall 11 and the surface of the gasket.

Then, as the receptacle moves relatively upwardly, it operates to bend the upper portion 40 of the gasket outwardly into the pocket 10, said pocket being, as before mentioned, capable of accommodating enough of the gasket material so that practically none of the gasket material will move to position 45 where it would be squeezed between the wall 6 and the upper edge of the receptacle.

Where desired, a liner, as 15, may be employed, and where employed it may consist of a disk of suitable material placed within 50 the closure prior to the formation of the gripping flange. In the instance illustrated, the disk is of such size that it normally projects over the upper edge of the gasket H prior to the formation of the gripping 55 flange, as in Fig. 3, it being moved upwardly into the bead by the formation of the gripping flange, as in Fig. 2. In some instances, the liner may be depended upon to constitute a seal between the closure and the receptacle, 60 since when the closure is applied the marginal portion of the gasket occupies a position between the closure and the upper and inner edge of the receptacle. The efficiency 65 of this seal, of course, is dependent upon the nature of the material employed for the

liner, and it has been found, in this connection, that a liner formed of suitably soft paper, coated, or impregnated, with such material as paraffin, or other oily substance, is well adapted to the purpose. When the 70 closure is forced downwardly on to the receptacle, the material of the liner is crushed into a sealing condition between the walls 5 and 6, and the receptacle, and the grip of the gripping flange against the outer surface 75 of the receptacle serves to hold the parts against any subsequent accidental movement.

The portion of the liner, standing between the wall 5 and the inner surface of 80 the receptacle, serves as a seal and may also be considered as a sort of protecting pad to prevent possible injury to the receptacle from the pressure of wall 5 thereagainst.

The closure, as described, consists of three 85 concentric annular walls, 5, 7 and 8. The wall, or flange, 8 occupies the intermediate position between the walls 5 and 7 and is resilient so that it is capable of movement toward or away from each of said walls 5 90 and 7. It is directly supported by the wall 7 which is also resilient although to a lesser degree than wall 8. The receptacle is held between the walls 5 and 8, and the wall 5, in addition to its function of affording a 95 seal for the receptacle, serves as an abutment assisting the receptacle in resisting the pressure of the wall 8 and the gasket. The gasket is held between walls 7 and 8 with its upper portion projecting into the space 100 to be occupied by the receptacle. The wall 8 provides a hard metallic surface along which the receptacle moves before engaging the gasket. This wall, by its downwardly diverging form, constitutes directing 105 means for directing the receptacle into proper association with the closure. During the operation of applying the closure, the receptacle is first brought into engagement with the inner surface of wall 8 and thereafter with the inner surface of the gasket appearing directly above the wall 8 so that thus the entering movement of the receptacle is made smooth and of uniform character at all times. Objectionable and non-uniform gripping of the gasket is entirely 110 avoided.

It is apparent that a closure constructed as herein described is capable of properly functioning upon different receptacles having a greater range of variation in diameter than the closures constructed as in said mentioned pending applications, this due primarily to the facility afforded for accommodating the upper annular portion of the 115 gasket, to avoid likelihood of movement of portions of the gasket to position directly above the edge of the receptacle.

Since the wall portion 11, as above shown, stands to receive and resist the maximum 120

sealing pressure between the gasket and the closure; that is, since between this wall portion and the receptacle occurs the greatest degree of squeezing of the gasket, it is apparent that said wall portion 11 may be correctly referred to in the claims herein-after as a sealing ridge.

It should be pointed out that during the application of the closure to a receptacle, the outward movement of the gripping flange, under pressure from the receptacle; that is, from the position shown by full lines to the position shown by dotted lines in Fig. 2, said flange operates to clamp the lower annular portion of the gasket against the wall 7 and beneath the shoulder 13, and thus prevents bodily upwardly movement of the gasket during the final movement of the closure on to the receptacle.

It may be noted further, in this connection, that although the drawings herein, and particularly Fig. 2, shows the gripping flange 8 shaped so that it normally stands away from the gasket, yet, if desired, it is wholly within the scope of this invention to so shape said flange that it will normally; that is, before application of the closure to the receptacle, rest against and hold the lower annular portion of the gasket in the manner just referred to.

In the latter instance, of course, the bending of the gripping flange by pressure from the receptacle will, of course, further and more securely grip the gasket.

As any changes could be made in this construction without departing from the scope of the invention as defined in the following claims, it is intended that all matter contained in the above description, or shown in the accompanying drawings, shall be interpreted as illustrative only and not in a limiting sense.

From one point of view, the invention herein, and particularly when the gripping flange 8 is bent, as last above mentioned, may be considered to comprise an annular marginal flange, the lower portion of which is shaped to provide a bead upon said flange within which is received and held the lower annular edge portion of the gasket so as to hold the gasket from bodily upward movement during the process of applying the closure to a receptacle. It is important to note in this connection that the bead is so constructed that it will be caused to take a firmer grip upon the gasket whenever it is called into use for retaining the gasket against dislodgement by the relatively upward movement of a receptacle into the closure. And also, that the larger the diameter of the receptacle, and consequently the greater the drag upon the gasket, then the tighter will be the grip of the bead upon the gasket to overcome the drag.

Having thus described my invention, what

I claim as new and desire to secure by Letters Patent is:—

1. A receptacle closure having a marginal portion adapted to overlie an exterior portion of a receptacle, said marginal portion having a receptacle gripping flange formed thereon bent inwardly and upwardly therefrom to provide an annular pocket between said gripping flange and said marginal portion, said marginal portion having also an annular sealing ridge formed thereon projecting inwardly in a position above said pocket, a gasket arranged within said pocket, having an annular receptacle engaging part projecting above the upper edge of the gripping flange, said part being adapted when the closure is applied to a receptacle to occupy a position between said sealing ridge and the outer surface of the receptacle, and said gripping flange being bendable and being adapted when applied to a receptacle to be bent by engagement with the receptacle for partially closing said pocket and for thereby squeezing a portion of the gasket upwardly from said pocket and into said first mentioned part, for the purpose set forth.

2. A receptacle closure having a marginal portion adapted to overlie an exterior portion of a receptacle, said marginal portion having a receptacle gripping flange formed thereon bent inwardly and upwardly therefrom to provide an annular pocket between said gripping flange and said marginal portion, said marginal portion having also an annular sealing ridge formed thereon projecting inwardly in a position above said pocket, a gasket arranged within said pocket, having an annular receptacle engaging part projecting above the upper edge of the gripping flange, said part being adapted when the closure is applied to a receptacle to occupy a position between said sealing ridge and the outer surface of the receptacle, and said gripping flange being bendable and being adapted when applied to a receptacle to be bent for partially closing said pocket and for thereby squeezing a portion of the gasket upwardly from said pocket and into said first mentioned part, and there being an annular pocket formed within the closure in a position above said sealing ridge, all for the purpose set forth.

3. A receptacle closure comprising a body part having an annular bead formed thereon, the bead providing a portion resilient for engaging the outer annular surface of a receptacle, a gasket held by said resilient portion in position to engage the receptacle, said resilient portion being positioned to be pressed by the receptacle against the gasket, and said bead providing a shoulder therein positioned to obstruct excessive displacement of the gasket when the gasket is pressed upon by said resilient portion.

4. A receptacle closure comprising a body part having an annular bead formed thereon, the bead providing a portion resilient for engaging the outer annular surface of 5 a receptacle, a gasket held by said resilient portion in position to engage the receptacle, said resilient portion being positioned to be pressed by the receptacle against the gasket, and said bead providing a shoulder therein 10 positioned to obstruct excessive displacement of the gasket when the gasket is pressed upon by said resilient portion, and said bead providing also an annular sealing ridge projecting inwardly thereof toward the receptacle in a position above said shoulder. 15

In testimony whereof I affix my signature in the presence of two witnesses.
